[57] CLAIM

The ornamental design for a simulative toy mobile, as
shown and described.

DESCRIPTION

FIG. 1 is a perspective view of a simulative toy mobile
showing my new design;

FIG. 2 is a top plan view thereof shown on a slightly
reduced scale;

FIG. 3 is a left side elevational view of the airplane
member shown on the left side of FIG. 1;

FIG. 4 is a front elevational view thereof;

FIG. 5 is a left side elevational view of the aerial mem-
ber shown on the right side of FIG. 1;

FIG. 6 is a front elevational view thereof; and

FIG. 7 is a rear elevational view thereof on a reduced
scale.

Portions of the support structure and tether members
have been omitted from FIGS. 3-7 for ease of illustra-
tion.
